COUPLER ATTACHMENT

Sigvard Simonson, Butler, Pa., assignor, by mesne assignments, to Hulson Company, Chicago, Ill., a corporation of Iowa.

Application March 4, 1949, Serial No. 79,656

11 Claims. (Cl. 213—8)

1

This invention relates to railway car underframes of the Duryea type, also frequently referred to as cushion type underframes, and more particularly to the provision therein of couplers capable of angling both vertically and horizontally relative to the underframe.

Underframes of the type mentioned above comprise a center sill or draft and buffing column extending substantially the entire length of the car body and movable longitudinally relative thereto when subjected to draft and buffing forces, such movement being yieldably resisted by suitable cushioning means of various well known types. Train slack, on the other hand, is independent of the sill travel, being predetermined by limiting the amount of movement of the couplers relative to the sill. As a rule, the couplers are permitted a small amount of inward movement relative to the sill on buff, which is yieldingly resisted by suitable resilient means, and these means are arranged so as to maintain the couplers normally in their extreme outward positions relative to the sill so that there is no slack in the case of draft forces. For the purpose of thus positioning the couplers, either the cushion gear springs or separate, relatively light coupler positioning springs can be used, both of these arrangements being well known in the art. Examples of such underframes are disclosed in the U. S. Patents 1,693,194 and 1,904,294.

Usually the coupler is connected to the sill by a horizontal coupler key slideable in longitudinal slots in the sill which are longer than the width of the key so as to permit the desired amount of travel of the coupler relative to the sill. This arrangement also permits horizontal angling of the coupler relative to the sill, due to the longitudinal play of the key in the slots, but is not suitable for use when substantial vertical angling is required, as for example in the case of vertically interlocking types of couplers.

The present invention eliminates the usual horizontal coupler key and avoids the use of slotted connections between the coupler and the sill, while at the same time it provides for both vertical and horizontal angling of the coupler relative to the sill. These results are accomplished by a novel construction that is strong as well as simple and inexpensive and that preserves unaltered the well known operation and advantages of the above described type of underframe.

One embodiment of the invention has been illustrated in the accompanying drawings, but it is to be expressly understood that said drawings are for purposes of example only and are not to

2

be construed as a definition of the limits of the invention, reference being had to the appended claims for this purpose.

In the drawings,

3 Fig. 1 is a sectional plan view of one end of an underframe embodying the invention;

Fig. 2 is a vertical section on the center line of Fig. 2;

Fig. 3 is a transverse section on the line 3—3 of Fig. 2;

Fig. 4 is a plan view of a follower plate construction;

Fig. 5 is a side view of Fig. 4; and

Fig. 6 is an end view of the follower construction.

The center sill itself may have any suitable construction known to the art. In the form shown, it comprises two Z-shaped sections 1 with their upper horizontal flanges meeting and 20 welded together along the center line of the sill as indicated at 2, and with their lower flanges 3 turned outwardly at the bottom of the sill. The sill proper thus has a hollow rectangular cross-sectional shape and is open at the bottom.

25 When subjected to draft and buffing forces, this sill moves longitudinally relative to the car body and bolsters in the manner illustrated by the prior patents mentioned above. The drawings show a part only of a cushion gear of one of the known types mentioned above, in which the main cushioning spring 4 extends outwardly from the car bolster (not shown) to a point near the butt of the coupler, its outer end being linked to the bolster by means of a link 5 having

35 a head 6 and a retaining plate 7. The details of the cushion gear at the bolster may correspond to those disclosed in various prior patents on this type of underframe, as for example U. S. Patents Nos. 2,284,268 and 2,349,656. The spring

40 4 is mounted within the sill 1 in any suitable way as by means of a housing 8. In this type of cushion gear, the spring serves also to position the coupler as mentioned above and as described in greater detail hereinafter.

45 The coupler 9 is mounted at the end of the sill with its shank 10 extending into the sill and connected to a follower plate 11 by means of a universal pivotal connection the details of which are described hereinafter. Thus the coupler and

50 follower move back and forth together in the sill in the longitudinal direction, without any relative sliding movement between them and regardless of angling of the coupler. On the other hand, both draft and buffing forces are transmitted to the sill by means of the follower plate which has a limited longitudinal movement between a draft lug and a buffing stop secured to

the sill. In this way slotted connections are eliminated, and there is no connection between the coupler and the sill so that the coupler can angle freely relative to the follower, while at the same time draft and buffing forces are effectively transmitted to the sill and the usual operation of this type of underframe is preserved unaltered.

Referring in greater detail to the particular embodiment of the invention shown in the drawings, the end of the sill is strengthened by a suitable end casting shaped to provide an opening through which the coupler shank extends and bridging the open bottom of the sill to support the coupler shank. This casting preferably comprises a top plate 12, side webs 13, and a horizontal bottom section 14 extending underneath and supporting the coupler shank 10, these portions defining a substantially rectangular opening in the end of the sill. Preferably the bottom section 14 includes a housing 15 containing a spring 16 which supports a carrier plate 17 on which the coupler shank rests, this arrangement permitting angling of the coupler but normally maintaining it in the horizontal position shown in the drawings. If desired, the side webs 13 may be extended inwardly and shaped to provide key slots 18 extending through the side walls of the sill so that the customary coupler and coupler key can be used, but it will be understood that these slots play no part in the operation of the present invention and can be omitted.

The follower 11 comprises a substantially rectangular plate movable longitudinally within the column and supported slidably on a bottom plate 19 secured to the lower flanges 3 of the sill. This follower is engaged by the head 6 of the link 5 and thus urged outwardly by the cushion gear spring 4 to the position shown in Fig. 1 in which the ends of the follower engage suitable draft lugs 20 secured to the side walls of the sill. As shown, these draft lugs are integral with and formed at the ends of the inwardly extending side webs 13 of the end casting described above, but they may be made as separate parts if desired. Accordingly when the follower is pulled outwardly by the coupler on draft, the pull is transmitted through the draft lugs 20 to the sill 1 and the sill moves outwardly relative to the car body without train slack. In the case of buffing forces, on the other hand, the follower 11 can move inwardly relative to the sill until it engages the end of the spring housing 8 which functions as a buffing stop, limiting such relative inward movement of the follower and thereafter transmitting the buffing forces from the follower to the sill and which may then move longitudinally relative to the car body.

Figs. 1 and 2 show a preferred form of universal pivotal connection between the coupler and the follower, and Figs. 4, 5 and 6 show the details of the follower itself whereby this connection is effected. Upper and lower supporting arms 21 and 22 respectively extend outwardly from the upper and lower edges of the follower between the draft lugs 20. The shank of the coupler is embraced between these arms, and the follower and coupler butt have cooperating spherical surfaces indicated at 23 whereby angling of the coupler in any direction relative to the follower can take place without interfering with the transmission of buffing forces from the coupler to the follower. Draft forces are transmitted from the coupler to the follower by means of a vertical pin 24 extending through an opening in the

coupler shank with its ends seated in openings in the upper and lower arms 21, 22 of the follower. As shown in Fig. 2, the pin is supported by means of the bottom plate 19 mentioned above. The connection of the coupler to the follower is completed by a bearing block 25 interposed between the inner side of the pin and the inner surface of the coupler butt, this block having a spherical surface engaging the corresponding spherical inner surface of the coupler butt as indicated at 26 and a cylindrical surface engaging the pin as indicated at 27.

The coupler can thus swing horizontally about the axis of the pin 24 for horizontal angling relative to the follower and sill, the spherical coupler butt turning against the spherical follower surface at 23. In order to provide for vertical angling of the coupler relative to the follower and pin 24, the outer side of the opening in the coupler shank tapers outwardly or away from the pin, this taper beginning at the center of the shank and increasing both upwardly and downwardly from the center as indicated at 29 in Fig. 2. This construction, together with the spherical engagement of the coupler butt with the follower at 23 and with the bearing block at 26, permits the coupler to tilt vertically relative to the follower and pin.

The operation will be understood from the foregoing description and may be summarized briefly as follows. On draft, the coupler pulls the follower through the pin 24 and this pull is transmitted through the draft lugs 20 to the sill 1. These parts being normally in engagement, the sill is pulled outwardly relative to the car body without train slack and this movement is cushioned by the cushion gear spring 4. On buff, the buffing force is transmitted from the coupler to the follower through the meeting spherical surfaces 23 and the follower moves inwardly relative to the sill until it engages the buffing stop formed by the spring housing 8, this movement being cushioned by initial compression of the cushion gear spring 4. Further inward movement of the coupler in the case of a strong buffing force results in moving the sill longitudinally relative to the car body with further compression of the cushion gear spring 4. Thus the normal operation of cushion underframes of this type is preserved unaltered but without slotted connections to the sill and in fact without any direct connection of the coupler itself to the sill. Hence the coupler is free to angle either horizontally or vertically relative to the follower plate as described above.

It will be understood that the invention is not restricted to the embodiment shown in the drawings nor to the details of the foregoing description, since other embodiments can be made as well as various changes in the form, details of construction and arrangement of the parts described above. Hence reference should be had to the appended claims for a definition of the limits of the invention.

What is claimed is:

1. In a railway car, a center sill movable longitudinally relative to the car body, a coupler having a shank extending into the end of said sill, a follower having a universal pivotal connection with the coupler shank, a draft lug secured to said sill and engaged by said follower to transmit draft forces from said coupler to said sill, means for cushioning movement of the sill relative to the car body including a spring engaging and normally maintaining said follower in

engagement with said lug, and a buffing stop secured to said sill and adapted to be engaged by said follower to limit inward movement of said follower and coupler relative to said sill from normal position and thereafter to transmit buffing forces from said coupler to said sill, said limited inward movement of said coupler and follower being cushioned by initial compression of said spring.

2. The construction defined in claim 1, comprising a pair of draft lugs one secured to each side of the center sill and engaged by the lateral edges of said follower, said buffing stop comprising a housing for said spring.

3. The construction defined in claim 1, said follower having outwardly extending upper and lower arms embracing the coupler butt, said coupler butt having an outer spherical surface engaging a cooperating spherical surface on said follower, a vertical pivot pin extending between said arms and through an opening in the coupler shank, and a bearing block in said opening having a cylindrical surface engaging said pin and a spherical surface engaging a corresponding inner spherical surface of the coupler butt, the outer side of said opening being enlarged relative to the pin to permit tilting of the coupler shank in a vertical direction.

4. In a railway car, a center sill movable longitudinally relative to the car body, a coupler having a shank extending into the end of said sill, and means mounting the coupler for limited longitudinal movement and for angling movement both vertically and horizontally relative to the sill, said means comprising a draft lug and a buffing stop secured to said sill, a follower movable longitudinally relative to the sill between said lug and stop, resilient means urging said follower outwardly toward said lug, and a universal pivotal connection between said follower and coupler shank to permit angling movement of the coupler, the engagement of said follower with said lug and stop transmitting draft, and buffing forces respectively from the coupler to the sill and moving the sill longitudinally relative to the car body.

5. In a railway car, a center sill movable longitudinally relative to the car body, a coupler having a shank extending into the end of said sill, and means mounting the coupler for limited longitudinal movement and for angling movement both vertically and horizontally relative to the sill, said means comprising a draft lug and a buffing stop secured to said sill, a follower movable longitudinally relative to the sill between said lug and stop, resilient means urging said follower outwardly toward said lug, spaced arms extending outwardly from said follower and embracing the coupler shank, the butt of the coupler having spherical engagement with said follower, and means connecting the coupler shank to said arms for pivotal movement about horizontal vertical axes, the engagement of said follower with said lug and stop transmitting draft and buffing forces respectively from the coupler to said sill and moving the sill longitudinally relative to the car body.

6. In a railway car, a center sill movable longitudinally relative to the car body, a coupler having a shank extending into the end of said sill, and means mounting the coupler for limited longitudinal movement and for angling movement both vertically and horizontally relative to the sill, said means comprising a draft lug and a buffing stop

secured to said sill, a follower movable longitudinally relative to the sill between said lug and stop, resilient means urging said follower outwardly toward said lug, spaced upper and lower arms extending outwardly from said follower and embracing the coupler shank, the butt of the coupler having spherical engagement with said follower to transmit buffing forces thereto while permitting angling of the coupler, and means connecting the coupler shank to said arms for pivotal movement about axes at right angles including a vertical pin extending through the shank and into said arms to transmit draft forces to said follower, the engagement of said follower with said lug and stop transmitting draft and buffing forces respectively to said sill and moving it longitudinally relative to the car body.

7. In a railway car, a hollow center sill movable longitudinally relative to the car body and having spaced, substantially parallel sides, a coupler having a shank extending into the end of said sill, and means mounting the coupler for limited longitudinal movement and for angling movement both vertically and horizontally relative to the sill, said means comprising draft lugs secured to the inner sides of the sill, a buffing stop secured to the sill inwardly of said draft lugs, a follower movable longitudinally relative to the sill between said lugs and stop, resilient means urging said follower outwardly toward engagement of its ends with said lugs, upper and lower arms extending outwardly from said follower between said lugs and embracing the coupler shank, and a universal pivotal connection between said shank and follower to transmit draft and buffing forces to the follower while permitting angling of the coupler, the engagement of said follower with said lugs and stop transmitting draft and buffing forces respectively from the coupler to the sill and moving it longitudinally relative to the car body.

8. The construction defined in claim 7, said follower comprising a plate extending laterally across the sill with its ends adapted to engage said lugs, said arms extending outwardly from the intermediate portions of its upper and lower edges.

9. The construction defined in claim 8, the outer surface of the follower plate between said arms being spherical for cooperating engagement with a spherical surface on the coupler butt to transmit buffing forces to the follower.

10. The construction defined in claim 9, said connection including a vertical pivot pin extending between said arms through an opening in the coupler shank for transmitting draft forces to the follower while permitting horizontal angling of the coupler relative thereto.

11. The construction defined in claim 10, the coupler butt having an inner spherical surface, and a bearing block interposed between said inner spherical surface and the pin and having a cooperating spherical surface and a cylindrical surface engaging the pin.
